FIG. 1 is a front elevation view of an appliance for preparing food and the like showing my new design;

FIG. 2 is a top plan view thereof;

FIG. 3 is a side view looking from the left side of FIG. 1 thereof;

FIG. 4 is a side view looking from the right side of FIG. 1 thereof;

FIG. 5 is a front elevation view of a modified form thereof;

FIG. 6 is a top plan view thereof;

FIG. 7 is a side view looking from the left side of FIG. 5 thereof; and

FIG. 8 is a side view looking from the right side of FIG. 5 thereof.

This application is a continuation of my copending applications Ser. Nos. D. 1,939 and D. 1,945, both filed Apr. 20, 1966 and both now abandoned.

The dominant features of my design reside in the portions shown in full lines.

I claim:

The ornamental design for an appliance for preparing food and the like, as shown and described.
